(57) **CLAIM**

The ornamental design for a modulator, as shown and described.

DESCRIPTION

FIG. 1 is a top perspective view of a modulator showing my design.

FIG. 2 is a left side view of the modulator of FIG. 1.

FIG. 3 is a top view of the modulator of FIG. 1.

FIG. 4 is a bottom view of the modulator of FIG. 1.

FIG. 5 is a front view of the modulator of FIG. 1.

FIG. 6 is a rear view of the modulator of FIG. 1.

FIG. 7 is a top perspective view of a modulator showing my design having certain features shown in phantom.

FIG. 8 is a left side view of the modulator of FIG. 7 having certain features shown in phantom.

FIG. 9 is a top view of the modulator of FIG. 7 having certain features shown in phantom.

FIG. 10 is a bottom view of the modulator of FIG. 7 having certain features shown in phantom.

FIG. 11 is a front view of the modulator of FIG. 7 having certain features shown in phantom; and,

FIG. 12 is a rear view of the modulator of FIG. 7 having certain features shown in phantom.

Elements of the modulator illustrated in broken lines are not intended to form part of the claimed design but merely exemplify one possible embodiment of the invention. Various omissions, replacements, and/or alternatives of the elements illustrated in broken lines can be utilized in the claimed design.
